(57) **CLAIM**

I claim the ornamental design for a spray bottle container, as shown and described.

DESCRIPTION

FIG. 1 is a top, rear and right side perspective view of a spray bottle container according to the present invention;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a bottom plan view thereof; and,

FIG. 7 is a top plan view thereof.

The broken lines shown in the drawing views are included for the purpose of illustrating environmental structure and form no part of the claimed design.
